UNITED STATES PATENT OFFICE.

LOUIS AUSTER AND MARIE AUSTER, OF NEW YORK, N. Y.

BATHING CAP.

Application filed April 2, 1923. Serial No. 629,456.

To all whom it may concern:

Be it known that we, LOUIS AUSTER and MARIE AUSTER, citizens of the United States, residing at New York city, in the county of 5 New York and State of New York, have invented new and useful Improvements in Bathing Caps, of which the following is a specification.

This invention relates to bathing caps, 10 devices and adjuncts therefor intended particularly for use by women bathers, and an object of the invention is to provide means to positively prevent water from entering the free edge and interior of the cap when 15 worn.

The invention has among its several objects certain new and novel improvements in construction and function arranged in a manner to effectively prevent the entrance 20 of water beneath the edge and interior of the cap and permit the cap to fit comfortably upon the head. Heretofore caps of this nature have been so formed that excess pressure and tension of the free edge thereof 25 is brought to bear against the head and ears and acts to retard free blood circulation, resulting in great discomfort to the wearer and frequent headaches and other objections.

By reason of our new and novel construction, means are employed for avoiding 30 the customary discomfort, inconvenience and annoyance caused by wet hair, as well as absolutely protecting the hair from injury due to the action of salt water.

A further object of the invention is to 35 provide the wearer with means of being relieved from the unavoidable and uncomfortable pressure of the cap against the ears due to tension when the cap is expanded beyond 40 its normal size and contracted against the head of the wearer.

In the ordinary manufacture of rubber 45 bathing caps, the bottom edges or bands thereof have been limited in construction and by necessity were cut on a straight line. The term "bottom edges or bands" is used to designate the part of the cap encircling the head from the forehead, against the ears and around the back of the neck. The object for cutting the lower edges or bands 50 on a straight line is for the purpose of creating a direct contracting force when the band embraces the head. Caps of this character are in general use and do not serve to effectively prevent the entrance of water to 55 the cap, irrespective of the force of pressure

of the band when contracted against the head. This is particularly due to irregularities in the contour of the head.

For example, when a rubber cap is 60 stretched over the smooth portions of the head such as the forehead, an effective resistance against the entrance of water results, but with the part of the cap stretched over and covering the ears and due to the 65 bony structures around the ears it has been impossible to close the joints at these points and at the neck and in consequence thereof water freely finds entrance to cap around the neck and ears. 70

Our invention has been designed to overcome the objections herein referred to and adapt itself to all irregularities of the head so as to uniformly seal the joint entirely around the head and positively prevent the 75 entrance of water into the cap.

With these and other objects in view, the invention resides in certain novel construction and combination and arrangement of parts, the essential features of which are 80 hereinafter fully described, are particularly pointed out in the appended claims, and are illustrated in the accompanying drawing, in which:—

Figure 1 is a perspective view of the cap 85 showing same applied.

Figure 2 is a perspective view showing the cap turned inside out.

Figure 3 is a vertical section through a portion of the cap showing the same applied. 90

Figure 4 is a side elevation of a slightly modified form of the invention.

Figure 5 is a top plan view thereof.

Figure 6 is a side elevation with parts in 95 section of a further modified form of the invention.

Figure 7 is a view similar to Figure 3 showing a still further modified form.

Figure 8 is a section taken approximately 100 on line 8—8 of Figure 2.

Figure 9 is a view similar to Figure 8 showing a modified form of a rib.

Figure 10 is a similar view of a further modified form of rib. 105

With reference to the form of the invention shown in Figures 1 to 3 inclusive and Figure 8, I provide a bathing cap 12 formed of rubber and consisting of an outer head enclosing body or member 13 and an inner 110 head embracing band or member 14, the latter being vulcanized or otherwise suitably

secured at 15 to one side of the body 13 above the reinforcing band or lower edge 16 thereof. Both of the members 13 and 14 are formed of rubber which may be reinforced in any suitable well-known manner. The band 14 is irregularly cut along its lower edge at 17 and at its upper edge is cut on an approximately straight line as at 18. The lower edge of the body 13 is cut on a straight line. The said band 14 is provided at its opposite sides between its front and rear ends with bifurcations 19 whose limbs are made to straddle the ears when the cap is worn. The portions in which the bifurcations are formed are preferably constructed of flexible inelastic waterproof material 20 which may consist of rubber coated textile material.

These portions 20 are bounded by arcuate laterally extending spacing ribs 21, the rear legs 22 of which are curved in conformation with the sides of the band rearwardly of said bifurcations and which extend at 23 to a point approximately in line with the medial part of the back of said band 14. This is clearly shown in Figure 5 and provides a flexible joint at the back of the band, whereby to permit the band to be folded in a flat package.

When it is desired to use the cap the band 14 is adjusted over the forehead so as to uniformly adapt itself to the contour thereof and the bifurcations 19 are made to accommodate the ears of the wearer. From the bifurcations the band is extended rearwardly of the ears and then against the back of the neck. By forming the portions 20 of inelastic material relatively permanent forms are given the bifurcations 19 so as to permit same to always comfortably adapt themselves to the ears. Band 14 is smooth on inner surface and when the band is adjusted as aforesaid the ribs 21 co-act with the portions 20 to define ear accommodating cavities as best illustrated in Figure 3. Assuming that the band has been operatively adjusted upon the head and around the ears, the outer body 13 is pulled downward so that the band 16 comes below the lower edge of the band 14 whereby to be contracted through the inherent action of the rubber and to engage against the forehead and at points beneath the ears and against the back of the neck so as to seal the joint between the cap and the head and positively prevent the entrance of water into the cap. The ribs 21 aside from serving to partly define accommodating cavities for the ears operate to form rests for the side walls of the body 13 when the latter is stretched over the head. This causes the base or band 16 of the body 13 to snugly accommodate itself to the head at points beneath the ears and around the back of the neck. In this manner the band 16 snugly conforms to irregularities of the

head at points where it has been impossible in bathing caps to properly seal the joint between the cap and the head while affording perfect comfort to the wearer. By causing the side walls of the body 13 to bear against the ribs we not only place these sides under slight tension but relieve the ears of the full pressure of these walls to thereby afford maximum comfort.

In Figure 4, the band 14^a is separate and may be used in connection with any suitable well-known form of elastic head covering wherein the band of the covering or free edge thereof is adapted to come below the lower edge of the band 14^a. In use of this form the band 14^a is adjusted to the head and an independent detached cap is then adjusted over the band to function in accordance with previous statements herein contained.

In Figure 6 the head covering member 13^a is formed of rubber and the base is irregularly curved at its free edge as shown at 13^b and bifurcated at its sides 13^c to accommodate the ears. Ribs 13^d extend around the bifurcations and the rear legs thereof are extended rearwardly at 13^e to a point medially of the rear of the body. Vulcanized or otherwise suitably secured to the body 13^a is an elastic skirt 13^f which extends below the free edge of said body. The invention is otherwise identical with the forms previously described and is a reversal of the form shown in Figures 1 to 3 inclusive but functions in exact agreement therewith.

In Figure 7 an inner member or band 14^b is employed and the bifurcated portion 14^c which embraces the ear is surrounded by an inwardly extending rib 14^d which bears directly against the head at points below the ears and against the sides of the head rearwardly of the ears. This is a reversal of any of the arrangements hereinbefore described but functions the same. The head covering 14^f is of elastic material vulcanized or otherwise suitably secured at 14^g to the band 14^b and adapted to extend over and embrace the same and to be terminally contracted at 14^h against the forehead, sides of the head, under the ears and against the back of the neck.

In Figure 9, a rib 21^a of circular formation is employed in lieu of the rectangular rib shown at 21. The rib 21^a may be formed of any suitable well-known elastic or cushioning material, preferably rubber and same is solid.

In Figure 10, the rib 21^b is preferably formed of hollow rubber tubing to render the rib highly buoyant or elastic.

While we have described what we deem to be the most desirable embodiment of our invention, it is obvious that many of the details may be varied without in any way departing from the spirit of our invention,

- and we therefore do not limit ourselves to the exact details of construction herein set forth nor to anything less than the whole of our invention limited only by the appended claims.
- 5 What is claimed as new is:—
1. In combination, a bathing cap, an elastic band within the cap, a rib for spacing the cap from the band at points on the cap where said cap embraces the ears and nape of the neck.
  - 10 2. In combination, a bathing cap, an elastic band connected to the cap along a vertical portion of said band, a rib for spacing the cap from said band at points on the cap where said cap embraces the ears and nape of the neck.
  - 15 3. In combination, a bathing cap, an elastic band within the cap, and means carried by the band for spacing the cap from the band at points on the cap where said cap embraces the ears, and for causing the periphery of the open end of the cap to engage the portions of the head which are adjacent the periphery of the cap and thereby seal the cap against passage of water.
  - 20 4. In combination, a bathing cap, an elastic band within the cap and provided with ear straddling cut-out portions to receive the ears, a rib for spacing the cap from the band at points on the cap where said cap embraces the ears and nape of the neck.
  - 25 5. In combination, a bathing cap having the edge of said cap at its open end formed along an irregular line with ear straddling cut-out portions, an elastic band of a width to include the full height of the ears, ribs surrounding the ear straddling
- portions and a rib connecting the first mentioned ribs and located at the back of said cap, said ribs elevating portions of the cap and compensating for the irregular contour of the head at the back of the ears and nape of the neck and causing said band to seal the cap against the passage of water.
- 40 6. A water guard for bathing caps comprising an elastic band of a width to include the ears of the wearer between the opposite edges of the band and provided with ear-shaped cut-out portions to receive and straddle the ears, substantially throughout their height, and ribs on the band spaced from and substantially paralleling the periphery of the cut-out portion.
- 45 7. A water guard for bathing caps, comprising an elastic band, an inverted substantially U-shaped rib on each side of said band adapted to protect the ears from the thrust of a cap.
- 50 8. A water guard for bathing caps comprising an elastic band, said band being provided with projecting means paralleling the ears to reduce direct pressure of a bathing cap upon the ears and for compensating for the irregular contour of the head behind the ears and nape of the neck.
- 55 9. A water guard for bathing caps comprising an elastic band provided with ribs paralleling the ears and terminating at one end at the rear and adjacent the lowest point of the ears, and a rib connecting said mentioned ends of the ribs.
- 60 In testimony whereof we have affixed our signatures.
